UNITED STATES PATENT OFFICE.

WATSON R. SMITH, OF JACKSON, MICHIGAN.

CUSHION-SPRING.

SPECIFICATION forming part of Letters Patent No. 792,083, dated June 13, 1905.

Application filed July 28, 1904. Serial No. 218,580.

To all whom it may concern:

Be it known that I, WATSON R. SMITH, a citizen of the United States, residing in the city of Jackson, in the county of Jackson and State 5 of Michigan, have invented certain new and useful Improvements in Cushion-Springs, of which the following is a specification.

My invention relates to spring - cushion work, and more particularly to means for 10 securing the springs of such cushions to their support or stay wires.

Another object of the invention is to provide an exceedingly simple, inexpensive, durable, and efficient means for the purpose 15 named.

A still further object of the invention resides in the formation of a clip or other element capable of receiving oppositely-arranged stay or supporting wires and securing them 20 firmly to springs, the clip being designed to be sprung into engagement with the wires and the springs at their points of intersection.

With these and other objects in view the present invention consists in the combination 25 and arrangement of parts, as will be herein-after more fully described, shown in the accompanying drawings, and particularly pointed out in the appended claims, it being understood that changes in the form, proportion, 30 size, and minor details may be made within the scope of the claims without departing from the spirit or sacrificing any of the advantages of the present invention.

In the drawings, Figure 1 is a perspective 35 view of a portion of a cushion, illustrating the manner in which a spring is supported upon longitudinal and transverse support - wires.

Fig. 2 is an enlarged detail perspective view 40 of a double-cone spring, illustrating the manner in which the stay or support wires and the spring are connected together at their points of intersection. Fig. 3 is an enlarged detail perspective view of the clip for securing the spring to the wire.

45 Referring now more particularly to the accompanying drawings, the reference character 1 designates transverse support or stay wires, while the reference character 2 indicates a longitudinal support or stay wire, the numeral 50 3 indicating a double-cone spring.

Double-cone springs are larger at their top and bottom than at their center portions, in view of which, unless there be means employed to prevent it, the middle portion is forced downwardly through the larger bottom 55 of the spring when pressure is brought to bear upon the cushion, the effectiveness of the spring being thereby affected. In order to connect the springs and stay or support wires rigidly together in the formation of open cushion-spring work and also to prevent the middle portion of double-cone springs from being forced downwardly through the base portion thereof when pressure is brought to bear upon the same, I arrange the transverse stay or support wires in pairs, and along the corresponding edges of the spring, and preferably, although not necessarily, at right angles thereto I dispose longitudinal stay or support wires 60 2, which are designed to cross the transverse 70 wires at a point where the longitudinal wires will be placed substantially across the middle portion at the top or bottom of the springs. These wires are held in such relation as that described through the instrumentality of detachable clips, which are preferably formed of a single piece of wire or other suitable material, each bent intermediate its ends to form an open loop or the like, 6, provided with a contracted throat, whereby the longitudinal support or 75 stay wire 2 may be sprung into engagement therewith, the free end of the clips being formed into hooks 7, sprung over the upper or lower convolutions of the springs and the transverse stay or support wires, all of which 80 85 is clearly shown in the accompanying drawings.

My peculiar arrangement possesses all the desirable features of a spring-cushion for beds, chairs, and the like, and in practice I have 90 found that whenever pressure is applied upon the cushion the pressure is directly upon the edge of the spring, and therefore there is absolutely no tendency of the wires turning upon the springs. Another advantage derived is 95 that when pressure is applied to any portion of the cushion it is distributed over the portion of the cushion surrounding that upon which the pressure is directly applied, and therefore the further the cushion is depressed 100

the larger the area over which the pressure is distributed, and consequently the greater will be the resistance of the cushion. A still further advantage resides in the fact that by 5 reason of the clips being sprung into engagement with the springs' stay or support wires the different elements are held in place even before the clips are tightened, thus rendering it much easier and more speedy to place the 10 different elements in position for final adjustment. A still further advantage resides in the fact that I am enabled to employ double-cone springs in a cushion without the employment of slats for the support of the springs, 15 which latter is a rather expensive arrangement. Moreover, when springs are mounted upon slats it is the custom to tie the springs together at their tops, which is an insecure method, and all of which I eliminate in the 20 present construction. I gain an advantage, too, over the old method of supporting the springs upon webbing, necessitating the tying of the springs at their tops, this method being also insecure. In other words, it has been 25 demonstrated that I can use support-wires formed in such manner as to be driven or otherwise secured in the framing of a couch, chair, bed, or vehicle seat-frame, my peculiar arrangement of the supporting-wires and their 30 connection with the clips associated therewith serving to bind the construction together rigidly. I am also enabled to make any irregularly-shaped construction to fit any frame or seat desired. Furthermore, I am enabled to 35 locate any particular spring forming part of my cushion.

I claim—

1. A clip for spring-cushion work, comprising a single piece of material bent intermediate 40 its ends to form a kink, and the free ends of the said piece of wire being directed in a plane common one to the other to form hooks, the kink being arranged in a plane at right angle to the plane of the hooks, the 45 kink and hooks being arranged in alinement.

2. In a spring-cushion, the combination with transverse and longitudinal support or stay

wires; of springs arranged with relation to said wires; and clips for securing the springs and the support or stay wires together, each 50 clip comprising a single piece of wire bent intermediate its ends to form a kink for the reception of a longitudinal support or stay wire, the free ends of each piece of wire being directed in a plane common one to the other to 55 form hooks, each hook engaging a transverse wire and the corresponding convolution of the adjacent spring, the kink being arranged in a plane at right angle to the plane of the hooks, and the kink and hooks being arranged in 60 alinement.

3. A clip for spring-cushion work, comprising a single piece of material bent intermediate its ends to form a kink, the open end of the kink being narrower than the remaining 65 portion thereof, and the free ends of said portions being directed in a plane common one to the other to form hooks whose open ends are narrower than the remaining portions thereof, the kink being arranged in a plane at right 70 angles to the plane of the hooks.

4. In a spring-cushion, the combination with transverse and longitudinal support-wires; of springs arranged with relation to the said wires; and clips for securing the springs and 75 the support or stay wires together, each clip comprising a single piece of wire bent intermediate its ends to form a kink for the reception of a longitudinal support or stay wire, the free ends of the wire being bent to form 80 hooks, each hook engaging a transverse wire and the corresponding convolution of the adjacent spring, the kink being arranged in a plane at right angle to the plane of the hooks and disposed between the inner side of the 85 convolution of the springs and the transverse wire with which said convolution contacts.

In testimony whereof I affix my signature in the presence of two witnesses.

WATSON R. SMITH.
